C. F. ZIEGLER.
SHOE TACKING MACHINE.
APPLICATION FILED FEB. 25, 1921.

1,386,752.

Patented Aug. 9, 1921.

INVENTOR:

CHARLES F. ZIEGLER,

Br: Otto H. Kueger,
his Atty.

UNITED STATES PATENT OFFICE.

CHARLES F. ZIEGLER, OF LOS ANGELES, CALIFORNIA.

SHOE-TACKING MACHINE.

1,386,752.

Specification of Letters Patent.

Patented Aug. 9, 1921.

Application filed February 25, 1921. Serial No. 447,674.

To all whom it may concern:

Be it known that I, CHARLES F. ZIEGLER, a citizen of the United States, residing at Los Angeles, in the county of Los Angeles 5 and State of California, have invented a new and useful Shoe-Tacking Machine, of which the following is a specification.

This invention relates to devices for repairing and tacking shoes.

10 One of the objects of this invention is to provide a device by which tacks can be inserted from the inside of shoes to be clenched through the seam to be connected, by the operation of a foot lever.

15 Another object is to provide a magazine for automatically feeding tacks through the one jaw member from the inside of shoes by the operation of a foot lever.

20 Other objects will appear from the following description and appended claims as well as from the accompanying drawing, in which—

25 Figure 1 is a side elevation of the device, partly in section and partly broken away to indicate where parts should preferably be lengthened to give the best results in operating the device.

30 Fig. 2 is a fragmentary detail side elevation of the upper termination of the tack selecting member, and the upper end or termination of the receiving tube.

Fig. 3 is a detail top plan view of the tack selecting member.

35 Fig. 4 is a detail front end elevation of the tack selecting member.

Fig. 5 is a fragmentary detail view partly in section of the operating and connecting bar and the upper jaw member.

40 The standard 6 is mounted on the base 7 for properly supporting the whole device. The foot pedal 8 is pivotally supported at 9, and has pivotal engagement at 10 with the operating bar 11. To allow properly guided movement of the foot treadle, a slot 12 is provided in the standard, and the ends of this slot serve to limit the vertical movement allowed to the foot treadle.

45 The foot pedal and the operating bar or rod 11 are automatically moved back to their inoperative positions and are normally held in their inoperative positions by a spring 13. This spring is disposed within the standard and surrounds the rod 11. The spring 13 is disposed between the inner terminations of screws 14 inserted in the standard and a pin 15 on the rod 11 so that a downward

movement of the foot pedal with the rod 11 will produce a compression of the spring 15. The expansion of the spring 13 when released, causes the return of the foot pedal 60 and the rod 11. The spring may, of course, be engaged by various other similar means between the standard and the rod without materially departing from the principle of the invention.

65 The relative movement between the two jaw members 16 and 17 is controlled by the foot pedal on the standard. The upper termination of the rod 11 is in operative connection with the jaw member 17. For certain reasons that will be set forth hereafter, the rod 11 must continue to move after the jaw 17 has reached its lowermost position. For this difference in the movements between the rod and the jaw member 17, the 70 telescopic engagement, illustrated in detail in Fig. 5, is preferred, where the spring 18 has one of its ends in engagement with the lower end of the arm 17 at 19 and its opposite end in engagement with a pin 20 on the 80 rod 11.

75 On a downward movement of the foot pedal 8, the rod 11 and the arm or jaw member 17 move in the same direction. As soon as the jaw end 21 of the member 17 85 comes into engagement with the jaw end 22 of the member 16, the movement of the member 17 comes to a stop while the rod continues to move downwardly thereby compressing the spring 18 within the member 17. 90

85 The double lever 23, pivotally supported at 24, engages at 25 with the operating rod 11. On a downward movement of the foot pedal 8, the end engaging with the rod 11 is moved to the position indicated at 26 in 95 dotted lines. The other end 27 of the double lever 23 is pivotally engaged to the nailing member 29, as indicated at 28.

90 The downward movement of the rod 11, after the jaw member 17 has engaged the 100 jaw member 16, serves mainly to operate the nailing member after the jaw ends 21 and 22 have come into contact. In inoperative position, the nailing member 29 is withdrawn from the end of the arm 16 so 105 as to bring the front end of the nailing member to a position indicated at 30. From this illustration it will be understood that the nailing member is quite a distance from the end 22 of the hollow jaw member 16 110 when the two jaw ends 21 and 22 become engaged, and that the continued downward

movement of the operating rod 11 will operate the nailing member 29 to drive a nail or tack from the hollow jaw member 16 against the end 21 of the jaw member 17.

5 A tack magazine 31 is provided for holding tacks ready to be used in this device. A tube 32 forms the communication between the magazine and the hollow jaw, and terminates near the end of the nailing member 10 when the same is in inoperative position, as indicated at 33. The termination of the tube 32 within the magazine is preferably beveled off as indicated at 34 and illustrated in Fig. 2 in detail.

15 A tack selector operating bar 35 is connected to the lever 23 and terminates within the magazine near the end 34 of the tube 32. A selecting member 36 is pivotally mounted on the termination of the selector operating 20 bar 35. The termination of the member 36 is notched or provided with an open fork-like engaging and selecting end 40, so that a tack 37 may rest in the fork-like opening of the selecting member 36 so as to point into 25 the tube 32 when the tack selector is in a position above the beveled termination of the tube 32. In descending, the member 36 pivoted at 39 on the end of the bar 35 tilts upwardly as soon as it strikes the tube 32 30 to the position indicated in dotted lines at 38.

The magazine is preferably kept full of tacks to a point just below the opening of the tube, so that the descending selector must dip and sink into the mass of stored tacks 35 thereby allowing tacks to come above the selecting member 36. Any tacks located above the selector are pushed upwardly when the selector is moved upwardly. The cut-out 40 is, however, proportioned so that only one 40 tack remains in the cut-out 40 with its point in the direction downwardly into the tube 32, and all other tacks fall off and out of the way so that the one selected tack may easily fall into the tube when the selector descends the 45 next time. The tube is made long enough, and the magazine is disposed high enough to cause the selected tack to slide through the tube into the hollow jaw member in front of the nailing member 29 ready to be pushed upwardly by the next movement of the device.

50 One quick and short movement of the foot

pedal brings the two jaw members into engaging position, one closely pressing against the other; presses the nailing member 29 in; 55 causes a new tack to be dropped into the tube; and allows the whole device to return quickly to inoperative position, the new tack dropping into position in front of the returned nailing member. Slight modifications may, of course, be made without departing from the principle of the invention, and I do not limit myself to the specific details described in this specification.

Having thus described my invention, I 65 claim:

1. In a sole tacker, a standard, a foot lever on the standard, a hollow clamping jaw on the standard projecting upwardly, a movable clamping jaw operative by the foot lever extending over and toward the first-named jaw, a nailing member within the first-named lower jaw, means for holding the jaws in clamping position, and means to operate the nailing member when the jaws are in 75 clamped position.

2. In a sole tacker, a hollow standard of suitable height to reach from the foot of the operator to a point near his hands, a foot 80 pedal near the lower end of the standard, an operating rod in the standard connected to the foot pedal, spring means in the standard surrounding the rod for holding the foot pedal in inoperative position, one jaw member rigidly provided on the standard near 85 the upper end of the standard, another jaw member telescopically connected with the rod and with the standard normally spaced from the first-named jaw member, a nailing member in operative connection with the rod terminating within the first-named jaw member and adapted to force a tack through the front end of said jaw member, and means 90 operative by said operating rod for transferring a tack from a magazine into a position 95 in front of the nailing member.

In testimony that I claim the foregoing as my invention I have signed my name in the presence of two subscribing witnesses.

CHARLES F. ZIEGLER
